UNITED STATES PATENT OFFICE.

WILLIAM PEARSON, OF KALISPELL, MONTANA.

DESIGN FOR A CLOTHES-PIN.

51,186.

Specification for Design.

Patented Aug. 21, 1917.

Application filed June 4, 1917. Serial No. 172,805. Term of patent 7 years.

To all whom it may concern:

Be it known that I, WILLIAM PEARSON, a citizen of Sweden, who has declared his intentions of becoming a citizen of the United States by filing his first papers to be a citizen of the United States, residing at Kalispell, in the county of Flathead and the State of Montana, have invented a new, original, and ornamental Design for a Clothes-Pin, of which the following is a specification, reference being had to the accompanying drawing, forming part thereof.

Figure 1 is a perspective view of a clothes pin showing my new design, and

Fig. 2 is an edge view thereof.

I claim:

The ornamental design for a clothes pin as shown.

WILLIAM PEARSON.
